US0D1014460S

(12) **United States Design Patent** (10) **Patent No.:** **US D1,014,460 S**
Chen (45) **Date of Patent:** **** Feb. 13, 2024**

(54) **HEADSET**

(71) Applicant: **SHENZHEN LIYIN ELECTROACOUSTIC TECHNOLOGY COMPANY, Shenzhen (CN)**

(72) Inventor: **Xiaochun Chen, Shenzhen (CN)**

(73) Assignee: **SHENZHEN LIYIN ELECTROACOUSTIC TECHNOLOGY COMPANY, Shenzhen (CN)**

(**) Term: **15 Years**

(21) Appl. No.: **29/813,054**

(22) Filed: **Oct. 26, 2021**

(30) **Foreign Application Priority Data**

May 12, 2021 (CN) 202130282828.1

(51) LOC (14) Cl. **14-01**

(52) U.S. Cl.

USPC **D14/205**

(58) **Field of Classification Search**

USPC D14/205, 206, 226; D29/112; 2/209; 381/380-381, 374, 370, 74

CPC H04R 25/00; H04R 25/02; H04R 1/1066; H04R 1/1016; H04R 5/033; H04R 5/0335; H04R 1/105; H04R 1/1091

See application file for complete search history.

Primary Examiner — Paula Allen Greene

(74) Attorney, Agent, or Firm — Georgi Korobanov

(57) **CLAIM**

The ornamental design for headset, as shown and described.

DESCRIPTION

FIG. 1 is a front view thereof;

FIG. 2 is a left side view thereof;

FIG. 3 is a bottom view thereof;

FIG. 4 is a top view thereof;

FIG. 5 is a rear view thereof;

FIG. 6 is a perspective view thereof; and,

FIG. 7 is another perspective view of a headset showing my new design.

The broken line depict portions of the headset that forms no part of the claimed design.

1 Claim, 6 Drawing Sheets
